UNITED STATES PATENT OFFICE.

WILLIAM G. KENDALL, OF NEWARK, NEW JERSEY, ASSIGNOR OF ONE-HALF TO
FREDERIC S. MASON, OF NEW YORK, N. Y.

BOX-FILLING MACHINE.

1,082,876.

Specification of Letters Patent.

Patented Dec. 30, 1913.

Application filed April 17, 1913. Serial No. 761,862.

To all whom it may concern:

Be it known that I, WILLIAM G. KENDALL, a citizen of the United States, residing at Newark, in the county of Essex and State of 5 New Jersey, have invented certain new and useful Improvements in Box-Filling Machines, of which the following is a specification.

My invention relates to mechanism for 10 filling small boxes and particularly to a mechanism for filling tablets into boxes.

The primary object of my invention is to provide means whereby tablets deposited initially in the hopper may be formed into 15 rows, each row containing a certain number of tablets and the rows of tablets carried into a box and deposited in their regular order.

A further object of the invention is to 20 provide means whereby tablets disposed in a hopper may be readily fed from the hopper in such manner as to prevent the tablets from jamming at the discharge mouth of the hopper and breaking.

25 A further object is to provide a tablet carrier adapted to be shifted into or out of position beneath the hopper, and to receive a definite number of tablets and arrange these tablets in certain regular order, this carrier 30 being movable away from the hopper to deposit the tablets in the boxes, the mouth of the hopper being closed by a cut-off movable with the carrier.

35 A further object of the invention is to provide in connection with a carrier having means for supporting tablets in rows, means for forcing the tablets out of the carrier and into position upon a table, and in this connection to provide means whereby the 40 rows of tablets after they leave the carrier may be shifted toward each other so as to decrease the area covered by the tablets and so that they may be deposited in a relatively small box in their proper position and order.

45 A further object is to provide a tilttable table and box support adapted to receive an inverted box and also receive upon its surface the ordered rows of tablets, the support being tilttable and being provided with a 50 plunger so that the tablets and the box may be inverted and the tablets discharged into the box in their regular order.

55 A further object of the invention is to provide a construction of the character stated which will require a minimum of at-

tention and whereby boxes may be expeditiously filled with tablets.

Other objects will appear in the course of the following description.

My invention is illustrated in the accompanying drawings wherein:

Figure 1 is a perspective view of a box filling machine constructed in accordance with my invention. Fig. 2 is a longitudinal section on the line 2—2 of Fig. 3. Fig. 3 65 is a plan view. Fig. 4 is a longitudinal section taken on the line 4—4 of Fig. 3. Fig. 5 is a perspective view of the box support detached. Fig. 6 is a longitudinal section of the box support and the table adjacent thereto, showing the parts in the position in which they are disposed when filling. Fig. 7 is a like view to Fig. 6 but showing the box supporting table inverted and the tablets deposited within the box. Fig. 8 is a 70 fragmentary cross section on the line 8—8 of Fig. 2. Fig. 9 is a detail view of the latch for supporting the plunger carrying members.

Corresponding and like parts are referred 80 to in the following description and indicated in all the views of the accompanying drawings by the same reference characters.

Referring now to Fig. 1, 2 designates a base plate of any suitable character and having thereon the upwardly extending supporting post 3. The upper end of this post supports a transversely extending plate 4 formed integral with a rearwardly extending sleeve 5. Superposed upon the plate 4 85 is a cap plate 6, and mounted upon this plate 6 is an angle-bracket 7. The rearwardly extending sleeve 5 forms a guide for a reciprocating rod as will be later described, and extending upward from the 90 sleeve 5 is a saddle 8 supporting bearings for an eccentric shaft 9. This shaft constitutes the driving shaft of the machine and is provided with a pulley 10 whereby power may be applied to the shaft to drive 95 it. The shaft 9 is formed with eccentrics 10^a which operate reciprocating rods 10^b whereby power is transmitted to the brushes 18.

Attached to the angle iron 7 and disposed 105 at the end of the sleeve 5 is a chamber 11 rectangular in form, the interior of the chamber being also rectangular and relatively narrow, the end walls of the chamber flaring outwardly as at 12 and resting 110

upon these end walls is a supporting plate 13 of any suitable material, preferably of hard fiber. Mounted upon the supporting plate is a cylindrical member 14 which constitutes a hopper. This is held in position against the plate 13 by means of vertically extending bolts 15, the lower ends of which are screw threaded and extend through the plate 13 while the upper ends are hooked, these hooks engaging over the upper edge of the hopper 14.

The upper face of the chamber 11 is flat and relatively wide. The under face of the plate 13 is transversely cut away as at 16 (see Fig. 8) to accommodate reciprocating rods 17 provided with inwardly projecting bristles 18. The plate 13 is formed upon its upper face with a transversely extending slot 19 which opens into the recess or cut-away portion 16, as illustrated in Fig. 8, to permit the tablets contained within the hopper 14 to pass downward between the reciprocating brushes 18 and into parallel guideways 19 formed within the chamber 11. The chamber 11 is divided longitudinally into these guideways by means of a longitudinally extending partition plate or septum 20, as seen most clearly in Figs. 3 and 8. The elongated passages 19 are of a size 30 adapted to receive a tablet when the tablet is on edge, but they are too wide to receive the tablet unless it is turned upon its edge. The object of the reciprocating brushes is to shift the tablets which are adjacent to the brushes so that all the tablets will eventually be turned from a horizontal position into a vertical position, and thus be in position to drop down through the passageways 19.

Disposed within the sleeve 5 is a guide rod 21 which is formed integral with a tablet carrier designated generally 22. This tablet carrier has the same cross sectional area as the chamber 11. The upper edge face of the carrier is rounded as at 23 and the under edge of the chamber 11 is concavely curved to snugly fit the curved edge 23. The interior of the carrier is divided into a plurality of elongated compartments, each compartment having a cross sectional area equal to the diametrical section of one of the tablets, each compartment being adapted however to contain a plurality of tablets.

In the form of my invention illustrated, the tablets are about the size shown in Fig. 2 and designated *a*, and under these circumstances the compartments are designed to receive about seven tablets. As shown in Fig. 9, the interior of the carrier is divided 55 longitudinally by means of a partition plate or septum 24 and transversely by means of septums 25. The carrier therefore will contain ninety-eight tablets altogether—forty-nine on each side of the septum 24 and 60 seven in each compartment of the carrier.

Extending downward from the end walls of the carrier are the guide rods 26, shown most clearly in Fig. 2, these guide rods being provided at their ends with nuts or heads 27. Mounted upon these guide rods is a slide 28. Disposed in each compartment of the carrier is a plunger 29, this plunger forming the inner extremity of a rod 30 whose other end is bifurcated as at 31 and is pivotally connected to the slide 28 at 32 for movement in a plane parallel to the plane of the slide. The upper face of the slide is provided with the button 33 whereby the slide may be handled. It is to be noted at this point that the shaft 21 is rotatable within the sleeve 5. When the carrier is in the position shown in Fig. 1 and beneath the chamber 11, the compartments in the carrier will be vertically disposed, one series of compartments alining with one of the passageways 19 and the other series with the other passageway 19, as illustrated in Fig. 8. The weight of the slide 28 holds the plungers 29 at the lower ends of the compartments of the carrier so that the tablets passing into the receiving chamber 11 will be directed into the compartments of the carrier and will fall therein in vertical rows, as illustrated in Fig. 2.

The receiving table upon which the tablets are designed to be deposited by means of the carrier 22, is mounted upon a standard designated 34. Disposed in this standard is a vertically adjustable post 35 carrying upon it the table 36. Formed integral with the table or otherwise rigidly connected thereto is a sleeve 37. Attached to the upper face of the table 36 are the laterally disposed marginal guide member 38, the rear inner faces of which are beveled outward and rearward as at 39. These marginal members 38 form side walls to the table and disposed between these marginal members 38 are a plurality of vertically disposed guiding strips 40. As will be seen from Fig. 3, there are four of these guiding strips 40 arranged in two pairs, one pair having a divergent relation to the other pair and each pair being arranged approximately parallel to the inclined faces 39 of the side guides or walls 38. In the construction illustrated, three tablets may be received between the rear ends of the inner guiding strips 40^a while the guiding strips 40^a are spaced each from the next adjacent guiding strip a distance equal to the diameter of one of the tablets, and this outer guiding strip is in turn spaced from the face 39 a distance equal to one of the tablets. The guideways formed between these guiding strips and the face 39 are thus adapted to register with the compartments in the carrier when the carrier is shifted outward from beneath the chamber 11 and into alinement with the table 36.

Extending into the sleeve 37 is a shaft 41 as illustrated in Fig. 4, this shaft carrying upon it a box support designated 42. This box support is in the form of a table, the under side of which is formed to receive and be rigidly attached to the shaft 41. The upper face of the table is formed with laterally disposed walls 43 of the same width as the walls 38 of table 36 and the length of the table is exactly the same as the length of a box A designed to receive the tablets.

The outer extremity of the table carries a plate 44 cut away to provide a central upstanding portion and two lateral upstanding tongues 45 which register with the walls 43. These tongues are adapted to engage an inverted box in the manner illustrated in Fig. 6. In order to center the box properly upon the box supporting table, I provide the laterally disposed blocks 46 which are held to the walls 43 by screws or other suitable devices. The inner faces of these blocks 46 are disposed outward of the inner faces of the side walls 43 as illustrated in Fig. 5. When the box A is inverted upon the box support as illustrated in Fig. 6, the side walls of the box rest upon the inner margins of the side walls 43 and the side walls bear against and are held against lateral displacement by the blocks 46. The side walls pass through the space between the tongues 45 and 44 and the box cover, if the cover is hinged to the box body, extends downward and outward. It will be seen that in this position which is that shown in Fig. 6, the inverted box body entirely covers the free space of the table 42. Disposed upon the face of the table is a plunger plate 47 which has the same area as the interior of the box A. The plunger plate is attached to a plunger rod 48 which extends down through the table 42 and projects below the same and is there provided with a handle 49. It will thus be seen that the table 42 may rotate from the position shown in Fig. 6 to the position shown in Fig. 7, and that when so rotated, the plunger plate will drop and carry whatever tablets there may have been deposited upon the plunger plate into the box.

In order to support the carrier in a horizontal position and in register with the entrance end of the table 36, I provide a latch designated generally 50 and illustrated in detail in Fig. 9. This latch is mounted in an upwardly extending supporting post or in any other suitable support which may be used, the post being designated 51. The latch is normally pressed outward by means of a spring 52 disposed within the post and engaging the reduced shank of the latch. The forward face of the latch on its under side is beveled as at 53. Normally the latch projects out into the path of movement of one of the guides 26 when the guide is

turned from a vertical to a horizontal position, and it will be obvious that as the guide moves upward past the latch it will engage the bevel face 53 and force the latch inward against the force of spring 52, and that as soon as the guide has passed the latch, spring 52 will force the latch outward again.

In order to permit the depression of the carrier from a horizontal to a vertical position, it is necessary to withdraw the latch and for this purpose I have provided a finger lever 54 which is pivotally supported upon the upper end of the standard 51 and which has an angularly extended end 55 engaging around the shank of the latch and engaging with a head 56 formed on the end of said shank. By a depression of the free end of this lever 54, the latch may be retracted.

The operation of my invention is as follows: The tablets which are about the size of those illustrated in Figs. 2 and 3 are filled into the hopper 14. No tablets can pass into the receiving chamber 11 unless they are turned upon their side as the compartments formed on each side of the septum 20 are only as wide as the thickness of one of the tablets. The tablets fall into the two passageways or guideways 19 as illustrated in Fig. 8. The dropping of the tablets into the passageways 19 is aided by the continual reciprocation of the brushes 17. This continual reciprocation is secured by connecting the wheel 10 to any suitable motor, or the wheel may be operated by hand. The bristles 18 of the brushes will not damage the tablets but merely agitate the tablets until they turn in a vertical position as illustrated in Fig. 8 and pass down into the passageways 19. At this time the carrier 22 is disposed beneath the chamber 11 in the position shown in Figs. 2 and 8. The tablets therefore are guided into the compartments from the hopper, these compartments being shown in Fig. 2. Each compartment is adapted to contain seven tablets. There are seven of these compartments on each side of the middle septum 24 and as a consequence the carrier is adapted to contain ninety-eight tablets altogether, in other words, just enough tablets to fill one of the boxes illustrated in Figs. 6 and 7. After the carrier has been filled it is moved outward and as it moves outward, the shaft or bar 21 acts as a cut-off closing the lower end of the compartment 11. When the carrier has been moved completely outward, it is in alignment with the receiving table 36 as illustrated in Fig. 3. The slide 28 is then moved inward by hand and the pushers or plungers 29 act to push the tablets out of the compartments of the carrier and onto the table 36. It will be understood that there are as many pushers or plungers as there are compartments in the carrier.

As the tablets and the plungers move forward onto the table 36, the outer tablets are guided inward or toward the longitudinal center of the table by means of the guides 40 and 40^a and the plungers are also guided in the same manner, this being permitted by reason that the plunger rods are pivoted at their rear ends to the slide 28. The slide 28 is pushed inward until the tablets have all been forced over onto the face of the plunger 47 in the position illustrated in Fig. 6. Previous to this, a box A has been placed upon the upper face of the box support and inverted over the plunger, the box being supported in such position however that the tablets may pass beneath the box. When the tablets have been deposited upon the face of the plunger 47, they will form a square as illustrated in Fig. 3, there being seven tablets on each side of the square and there being two layers of these tablets. When the tablets have been entirely deposited upon the plunger 47, the box support is rotated to the position shown in Fig. 7, whereupon the plunger will fall carrying the tablets down into the box. The box is then removed and the carrier returned to its original position for a new charge. Heretofore these boxes containing small tablets of this character have been filled by hand, an operation requiring about five or six minutes inasmuch as the tablets have to be arranged by the use of small pincers and pointed instruments. With my device, a box can be filled in about a half a minute and absolutely no skilled labor is required to do so.

While I have illustrated the mechanism which is operated entirely by hand, I wish it understood that I do not intend to be limited to this as it is obvious that the means for reciprocating the carrier and rotating it and operating the plungers might be automatic in their action. My invention is very effective for the purpose intended, is simple in construction, easy to operate and has no complicated parts to get out of order.

What I claim is:

1. In a box filling mechanism, a vertically disposed hopper, a carrier movable into and out of position beneath the discharge opening of the hopper, the carrier being mounted for rotative movement from a horizontal into a vertical position, stops for limiting the rotative movement of the hopper, a plunger disposed in the carrier and movable therethrough, and a horizontally disposed receiving table with which the carrier registers when turned into a horizontal position.

2. In a box filling mechanism, a hopper having a discharge opening, a carrier rotatably and slidably mounted beneath the hopper, the carrier being rotatable from a vertical to a horizontal position and slidably into and out of position beneath the discharge opening of the hopper, a receiving

table, and means for discharging tablets from the carrier onto said receiving table.

3. In a box filling mechanism, a hopper having a discharge opening, a rotatably and slidably mounted carrier movable into and out of position beneath the discharge opening of the hopper and rotatable from a vertical to a horizontal position, plungers mounted within the carrier normally at the lower end thereof, and a horizontally disposed receiving table with which the carrier is adapted to register when moved out of engagement with the hopper and turned into a horizontal position.

4. In a box filling mechanism, a hopper having a discharge duct leading therefrom, the duct being longitudinally divided into two halves, a carrier rotatably and slidably mounted, said carrier being divided by a partition into two halves corresponding to the two halves of the duct, plungers disposed in each of the compartments so formed, and a receiving table with which the carrier is adapted to register when moving out of engagement with the hopper and turned to a horizontal position.

5. In a box filling machine, a hopper having a discharge duct leading therefrom, the duct being relatively long and relatively narrow and being divided longitudinally into two halves, a carrier movable into and out of position beneath said duct and having the same cross sectional area as the duct, the carrier being divided by a longitudinal partition into two lateral halves, said halves being in turn divided into a plurality of compartments by means of transverse partitions, plungers operable through said carrier, means for rotating the carrier from a vertical position to a horizontal position, and a receiving table with the face of which the opening in the carrier is adapted to align when the carrier is turned to a horizontal position.

6. In a box filling machine, a hopper, a chamber disposed beneath the hopper and formed with a vertically disposed duct, a carrier movable into and out of position beneath said chamber and having a plurality of vertically disposed compartments, a shaft upon which the carrier is mounted, the shaft being shiftable with the carrier and acting as a cut-off closing the mouth of said duct when the carrier is shifted outward and away from registration with the duct, a horizontally disposed receiving table into registry with which the carrier may be turned, and means moving with the carrier for discharging the contents of the carrier upon said receiving table.

7. In a box filling machine, a hopper, a chamber disposed beneath the hopper and formed with a vertically extending duct, the lower face of the chamber being concavely rounded, a shaft rotatably and slidably

mounted in alinement with the under face of the chamber, a carrier mounted upon the shaft and having a convex face conforming to the concave face of the chamber, a horizontally disposed receiving table mounted to one side of the said chamber, the carrier being shiftable from beneath the chamber into a position in alinement with the receiving table and being rotatable from a vertical position to a horizontal position, plungers disposed within said carrier and adapted to discharge the contents of the carrier upon the receiving table, a box support rotatably mounted adjacent the receiving table and having a plunger whose upper face is flush with the receiving table, means for supporting a box in an inverted position upon the box support, and means whereby the box support may be inverted to permit the plunger to carry the article supported thereon into said box.

8. In a box filling machine, a carrier longitudinally shiftable and rotatable from a vertical to a horizontal plane, the interior of the carrier being divided into a plurality of compartments, guide rods extending from the carrier, a slide mounted on the guide rods, a plurality of plungers, one for each of said compartments mounted at their ends in said slide, means for discharging tablets into the carrier, and a receiving table upon which the carrier discharges when turned to a horizontal position.

9. In a machine for filling boxes with tablets, a receiving table having a plurality of guide walls converging for a portion of their length, and a plurality of plungers disposed between each pair of guide walls and movable longitudinally therebetween and adapted to shift rows of tablets along the face of the plate parallel to the guide walls to thereby cause the rows of tablets to be longitudinally shifted and simultaneously brought nearer to each other.

45 10. In a machine for filling boxes with tablets, a receiving table having side walls converging for a portion of their length and spaced guides extending parallel to the side walls, of means for discharging rows of tablets upon the face of said receiving plate and for shifting the tablets along the face of the plate parallel to the side walls of the guides to thereby cause the rows of tablets to be brought nearer to each other, and a box support arranged adjacent to and flush with the receiving table and having side walls and an end wall and including means for supporting a box in an inverted position.

11. In a machine for filling tablets into boxes, a hopper, a tablet carrier, means intermediate of the carrier and hopper for arranging the tablets in the same vertical plane and discharging them into said carrier, means for shifting the carrier out from beneath the hopper and rotating the carrier

into a horizontal plane, a receiving table upon which the carrier is adapted to discharge, means on the receiving table for causing the rows of tablets as they pass the receiving table to be shifted toward the longitudinal axis of the receiving table, a rotatable box support having its face flush with the receiving table, means for supporting a box in an inverted position thereon, and means for moving the contents of the carrier over the face of the receiving table and onto the face of the box support.

12. In a machine for filling tablets into boxes, a receiving table having side walls, the rear ends of the side walls having divergent relation, guides extending parallel to the side walls and spaced therefrom, guides intermediate the last named guides and disposed parallel to the longitudinal axis of the receiving table and spaced from each other, a box support mounted in proximity to the table and flush therewith, means for supporting a box in an inverted position upon the box support, and means for discharging rows of tablets upon the receiving table and between said series of guides.

13. In a machine for filling boxes with tablets, the combination with a receiving table having side walls, the rear portions of which have divergent relation to each other, guides spaced from the side walls and from each other and extending parallel to the rear portions of the side walls, intermediate guides between the first named guides, of a tablet carrier movable into alinement with the receiving table and being divided into a plurality of compartments adapted to aline with the spaces between said guides, a slide mounted upon said carrier, and a plurality of plungers pivotally mounted upon said slide, one for each of said compartments, said plungers having movement in a vertical plane whereby to permit the plungers to be laterally shifted by said guides on the receiving table.

14. In a machine for filling boxes with tablets, a box support rotatable in a vertical plane, a plunger mounted upon and constituting the face of the box support, means for supporting a box in an inverted position over said plunger, means for arranging tablets in a plurality of rows, and means for discharging said tablets upon the face of the plunger.

15. In a machine for filling boxes with tablets, a carrier slidably and rotatably mounted and divided into a plurality of compartments, a plurality of plungers closing the outer ends of said compartments, a slide mounted upon the carrier and to which the plungers are connected, means for discharging the tablets into the compartments of the carrier, a horizontally disposed receiving table into alinement with which the carrier is adapted to be shifted, means for support-

ing the carrier in a horizontally disposed position in register with the face of the receiving table, and a box support mounted beyond the receiving table and having means 5 for supporting a box in an inverted position, said box support including a plunger normally flush with the face of the receiving table.

16. In a machine for filling boxes with 10 tablets, a box support rotatable in a vertical plane and normally supported in a horizontal plane, said box support being adapted to support a box in an inverted position over the face of the support, means for arranging 15 tablets in a plurality of separated rows, means for causing the tablets to move laterally toward each other to thereby contract the width of the space occupied by the tablets, and means for discharging said tablets 20 upon the face of the box support.

17. In a machine for filling boxes with

tablets, a box support rotatable in a vertical plane and normally supported in a horizontal plane, a receiving table horizontally disposed flush with the face of the box support when the latter is in a horizontal position, means for arranging tablets in a plurality of separated rows, means for shifting said rows of tablets across the face of the receiving table and onto the face of the box 25 support, and means acting while the tablets are being shifted across the face of the receiving table for guiding said rows toward each other and toward the longitudinal axis of the receiving table to thereby contract the 30 total width covered by the rows of tablets.

In testimony whereof I affix my signature in presence of two witnesses.

WILLIAM G. KENDALL. [L. S.]
